EDWIN J. SCHNEIDER, OF JAMAICA, AND MERRITT B. BRADT, OF BROOKLYN, NEW YORK, ASSIGNEES, BY MESNE ASSIGNMENTS, TO GENERAL CABLE CORPORATION, OF NEW YORK, N. Y., A CORPORATION OF NEW JERSEY

ELECTRIC CONDUCTOR

Application filed July 7, 1926, Serial No. 120,896. Renewed February 10, 1932.

This invention relates to electric conductors or cables commonly used in the wiring of buildings for the supply of house current thereto for lighting or other purposes; and the object of the invention is to provide an improved conductor having the usual wire or strand encased in a rubber jacket or housing with a plurality of jackets, casings or enclosures mounted upon the wire of said rubber jacket, two of said enclosures being wound on said rubber jacket and one directly upon the other in opposite directions, and one of said wound jackets involving a weave structure to give strength and durability to the finished product; a further object being to provide enclosures composed of such material as to give the greatest possible strength to the finished conductor and also permitting of the required flexibility therein without subjecting said coverings to breakage or rupture; a further object being to provide an outer casing or jacket preferably composed of braided fabric, two of the conductors or wires with the coverings thereon being included in said jacket, and means being provided to fill the crevices between the separate conductors; a still further object being to provide a wrapped covering composed of a plurality of strands of twisted paper, said strands being wound upon the conductor in the formation thereof in multiple, to facilitate quick production and further to provide greater flexibility in the finished product; a further object being to treat the several casings or jackets employed to render the same waterproof by saturating or otherwise applying a waterproof composition to said coverings; and with these and other objects in view, the invention consists in an electric insulated conductor of the class described, which is simple and strong and durable in construction, efficient in use, and which is constructed as hereinafter described and claimed.

The invention described and claimed herein is an improvement on that shown and described in a prior application filed by us, February 15, 1926, and bearing Serial No. 88,228, and is fully disclosed in the following specification, of which the accompanying drawing forms a part, in which the separate parts of

our improvement are designated by suitable reference characters in each of the views, and in which:—

Fig. 1 is a detail view of a part of an electric conductor employing two metallic conductors contained within a single casing, illustrating the several protective casings or jackets employed thereon. 55

Fig. 2 is a transverse section on the line 2—2 of Fig. 1. 60

Fig. 3 shows detail view of a paper strip employed in the structure shown in Fig. 1 in extended, partially folded and fully folded positions; and, 65

Fig. 4 is a view similar to Fig. 1 but showing a modification. 65

In Figs. 1 and 2, 5 represents two metallic conductors each of which is provided with casings or jackets of similar construction and composed of insulating and protective material. To simplify the description, the coverings or jackets of one of the conductors only will be described, like reference being applied to both conductors. 70

Enclosing the conductor 5 is a comparatively heavy jacket composed, in the construction shown, of parallel strips of material 8 preferably paper, spirally wound in multiple directly upon the rubber jacket 6, with a plurality of binding strands 9 interwoven therewith and extending longitudinally of the conductor 5, the strands 9 consisting of cords, twisted paper strands or like material, and being so arranged that each strand passes first over one of the strips 8a and then beneath adjacent strips 8b as seen in Fig. 1 of the drawing. Adjacent strands 9 alternately pass over and under each of the strips 8a—8b. 80

In the construction shown, each strand 9 is composed of a plurality of segments, but a single strand may be employed, and it will also be understood that the showing in the drawing is exaggerated as to size and dimensions for the purpose of clearly illustrating the invention. 90

Wound upon the casing or jacket 7 is another casing or jacket 10 which in the construction shown, comprises a plurality of strands 11 arranged in multiple and paral-

lel relation, and collectively and directly wound upon the casing or jacket 7, in a direction opposite that of the winding of the casing or jacket 7 as clearly seen. The strands 5 11 of the casing or jacket 10 may be composed of twisted paper or of any other suitable material, paper being preferably employed in that the cost thereof is comparatively low as compared with strands composed of other material. It will also be understood that the casings or jackets 7 and 10 will be treated with a waterproof and fire-proof composition to protect the conductors to the greatest possible degree. In the completion of a conductor composed of parallel metallic conductors 5, each of which are jacketed as above described, the same are enclosed in a casing or jacket 12 preferably of braided fabric and treated with a waterproof 20 and fireproof composition, and the crevices between the adjacent wrapped conductors are filled in by filler cords 13 to form a neat and finished product, said cords being seen in Figs. 1 and 2 of the drawing. It will be understood that our invention is not limited to the use of two conductors, as a single conductor may be constructed and enclosed in a braided jacket as will be apparent.

In Fig. 3 of the drawing, we have shown 30 three views of a part of one of the strips 8 to indicate the manner of its construction, the strip being comparatively wide and folded upon three lines x , x_2 and x_3 to produce in the resulting product, a paper strip of four-ply thickness as seen at y in Fig. 3 of the drawing, the first fold in the formation of the strip being shown at y_2 wherein the sides of the sheet are folded inwardly on the lines $x-x_3$, and the last fold being on the line x_2 40 to bring the two folded sides adjacent. A strip of this kind will be strong and durable, and will provide a very desirable casing or jacket for enclosing the rubber casing or jacket 6, the strips 8 being reinforced and strengthened by the strands 9 interwoven therewith, and by extending said strands longitudinally of the conductor, great strength and durability is produced and yet sufficient flexibility maintained to suit the requirements.

In Fig. 4 of the drawing, a slight modification is shown, wherein a casing or jacket 14 is substituted for the casing or jacket 7 and instead of being composed of strips of paper 8 50 as in Fig. 1 of the drawing, the same is composed of two strand-like bodies 15, each composed of a plurality of strands 16 of twisted paper or any other desired material arranged in parallel relation and collectively and spirally wound upon the rubber jacket 6 with fibrous strands 17 interwoven with the separate bodies 15a and 15b in the same manner as the weaving of the strands 9 with the strips 8a and 8b.

With the form of construction shown in

Fig. 4, a casing or jacket 18 similar in all respects to the casing or jacket 10 is also employed, but wound in an opposite direction to the winding of the bodies 15. The separate conductors are enclosed in a casing or jacket 19 similar to the casing or jacket 12, it being understood that the metallic conductors 5a and the rubber insulation or jacket 6a are the same as the conductor 5 and jacket 6 as seen in Fig. 1 of the drawing.

It will be understood that the separate coverings or jackets employed in the structure shown in Fig. 4 may be treated with the waterproof and fireproof composition in the same manner as in the construction of the conductor shown in Figs. 1 and 2. By constructing the bodies 15 of separate strands 16 instead of a flat paper sheet, we provide a greater flexibility to the resulting product, and yet maintain a practical and strong and durable construction, which by virtue of the increased flexibility will not readily rupture or break.

In the construction shown in Fig. 4, it will be understood that the longitudinal strands 17 are interwoven with the collective multiple strand bodies, collectively wound upon the rubber jacket 6. It will also be understood that by employing a multiple strand body in both or one of the protector casings and in the use of comparatively small strands such as twisted paper, the pitch of the windings of the separate strands in each multiple body is comparatively great, thus rendering the resulting product or conductor very flexible. By virtue of the comparatively small radius of each strand, the possibility of opening the protector casing or casings is practically obviated. In addition, said strands give great strength and durability to the conductor. The longitudinal strands of the woven protector casing, in addition to reinforcing said casing, also reinforces the wire or conductor 5, especially when subjected to longitudinal stress or pull.

While we have shown and described certain details of construction for carrying our invention into effect, it will be understood that we are not necessarily limited to the specific structural details herein shown and described, and various changes therein and modifications thereof may be made within the scope of the appended claims without departing from the spirit of our invention or sacrificing its advantages.

Having fully described our invention, what we claim as new and desire to secure by Letters Patent, is:—

1. An article of manufacture, comprising in combination with a metal electric conductor, a body of insulating material surrounding said conductor, a protector covering mounted upon said body and comprising a multiplicity of strands arranged and wound side by side collectively and spirally on said

- body, and a plurality of strands arranged in circumferentially spaced relation and extending longitudinally of and in substantially parallel relation to the conductor and interwoven with the windings of said multiple strands extending alternately above and beneath the collective strands of the separate windings. 2. An article of manufacture, comprising in combination with a metal electric conductor, a body of insulating material surrounding said conductor, a protector covering mounted upon said body and comprising a multiplicity of strands arranged and wound side by side collectively and spirally on said body, a plurality of strands extending longitudinally of the conductor and interwoven with the windings of said multiple strands extending alternately above and beneath the collective strands of the separate windings, and another protector casing consisting of a multiplicity of strands arranged side by side and collectively and spirally wound directly upon the first named casing. 3. An article of manufacture, comprising in combination with a metal electric conductor, a body of insulating material surrounding said conductor, a protector covering mounted upon said body and comprising a multiplicity of strands arranged and wound side by side collectively and spirally on said body, a plurality of strands extending longitudinally of the conductor and interwoven with the windings of said multiple strands extending alternately above and beneath the collective strands of the separate windings, another protector casing consisting of a multiplicity of strands arranged side by side and collectively and spirally wound directly upon the first named casing, and two of the conductors thus formed being enclosed in a braided casing, and all of said casings being treated to render the same moisture and fire proof. 4. An article of manufacture comprising a metal conductor, a body of insulating material encircling said conductor, a woven casing on said body and consisting of spirally wound strips, and longitudinal strands arranged in substantially parallel and circumferentially spaced relation to said conductor and interwoven with said strips, another protector casing comprising a plurality of strands arranged in parallel relation and collectively and spirally wound directly on the woven casing. 5. An article of manufacture comprising a metal conductor, a body of insulating material encircling said conductor, a woven casing on said body and consisting of spirally wound strips and longitudinal strands interwoven with said strips, another protector casing comprising a plurality of strands arranged in parallel relation and collectively and spirally wound directly on the woven casing in a direction opposite to that of the winding of the strips of the first named casing, and a braided casing mounted upon the last named casing. 6. An article of manufacture comprising a metal conductor, a body of insulating material encircling said conductor, a woven casing on said body and consisting of spirally wound strips and longitudinal strands interwoven with said strips, another protector casing comprising a plurality of strands arranged in parallel relation and collectively and spirally wound directly on the woven casing in a direction opposite to that of the winding of the strips of the first named casing, a braided casing mounted upon the last named casing, and all of said casings being treated by a water and fire proof compound. 7. An article of manufacture of the class described comprising electric conductors, each contained in a body of insulating material, a woven protective casing mounted on each of said bodies, another casing spirally wound on each of the first named casings, the inner casings comprising longitudinal strands arranged in substantially parallel and circumferentially spaced relation to said conductors and interwoven with spirally arranged strips, and the outer casings being composed of a plurality of paper strands arranged side by side and wound in multiple directly upon the first named casings in a direction opposite to that of the spirally arranged strips of the inner casings. 8. An article of manufacture of the class described comprising electric conductors, each contained in a body of insulating material, a woven protective casing mounted on each of said bodies, another casing spirally wound on each of the first named casings, the inner casings comprising longitudinal strands arranged in substantially parallel and circumferentially spaced relation to said conductors and interwoven with spirally arranged strips, the outer casings being composed of a plurality of paper strands arranged side by side and wound in multiple directly upon the first named casings in a direction opposite to that of the spirally arranged strips of the inner casings, and both of said conductors thus formed being enclosed in a braided casing or jacket, and all of said casings being treated to render the same fire and moisture proof. 9. An article of manufacture comprising in combination with a metal electric conductor having a body of insulating material thereon, a protector covering forming a casing for said insulated conductor and comprising strands spirally wound in multiple on said conductor and including cord-like strands arranged in substantially parallel and circumferentially spaced relation to said conductor and interwoven with said spirally

wound strands extending alternately above and beneath said strands.

10. An article of manufacture comprising, in combination, a metallic conductor, a body of flexible plastic insulating material surrounding the same, a braided jacket mounted directly upon said body of plastic insulating material, wherein binding strands are interwoven with a multiple wrapping 10 of strip material to form a flexible covering, a wrapping of fibrous material mounted upon said braided jacket, and a fibrous protective sheath over the whole.

11. An article of manufacture comprising, in combination, a conductor, a body of flexible insulating compound surrounding said conductor, a braided jacket mounted directly upon said compound, wherein longitudinal strands are interwoven with a multiple wrapping of fibrous material, a multiple wrapping over said braided jacket and a covering over the whole provided with a protective compound.

12. An article of manufacture comprising, in combination, a conductor, a body of flexible insulating compound surrounding said conductor, a braided jacket mounted directly upon said compound, wherein longitudinal strands positioned in circumferentially spaced relation are interwoven with a multiple wrapping of fibrous material, and a multiple strand wrapping surrounding said braided jacket.

13. A non-metallic sheathed conductor comprising, in combination, a metallic conductor, a sheath of plastic insulating compound surrounding said metallic conductor, a braided jacket mounted directly upon said sheath and formed of paper elements interwoven with fibrous elements, a paper wrapping over said braided jacket and mounted directly thereon, an outer fabric jacket surrounding said paper wrapping, and a fire- and moisture-proofing compound applied to 45 said outer jacket.

14. An article of manufacture comprising in combination a metallic electric conductor, a body of insulating material surrounding said conductor, a protector covering comprising flat strip fibrous material wound upon said body of insulating material in pairs and arranged in edge to edge relation, and relatively small fibrous strands extending longitudinally of the conductor and interwoven with the strips of said protector covering.

15. An article of manufacture of the class described comprising electric conductors, each contained in a body of insulating material, a protector casing on the body of each of said conductors and composed of strip material wound in pairs with the separate strips in an edge to edge relation, another protector casing composed of strip material wound in multiple directly upon the first

named casing, the conductors thus formed being placed in parallel relation, a casing or jacket encircling both of said conductors, and a plurality of fibrous strands spaced circumferentially and extending longitudinally of each conductor and interwoven with the strip material of one of the casings thereof. 70

16. An article of manufacture comprising a metal conductor, a body of insulating material encircling said conductor, a flexible casing formed from flat strips of paper wound in multiple upon said body and forming a protector therefor, another flexible casing composed of strips of paper wound in multiple directly upon the first named casing, and a plurality of relatively small strands interwoven with the strips of one of said casings and extending in substantially parallel relation to said conductor. 75

17. An article of manufacture comprising, in combination, an electrical conductor, and insulating means therefor, comprising a covering of plastic insulating material, a pair of paper wrappings wound directly one upon the other over said plastic insulating material, one of said paper wrappings having relatively small reinforcing strands interwoven therewith, and a protective jacket for said wrappings. 80

18. An article of manufacture of the class described comprising a plurality of electric conductors, each of which is contained in a body of insulating material, a protector casing on the body of each of said conductors and composed of strip material wound in multiple with the separate strips in edge to edge relation, another protector casing composed of a multiple wrapping positioned directly upon the first-named casing, a casing or jacket encircling both of said conductors, and a plurality of spaced fibrous strands extending substantially longitudinally of at least one of said conductors and interwoven with the material of one of said casings. 90

19. An article of manufacture comprising an electric conductor, a body of insulating material surrounding said conductor, a flexible casing formed from flat strips of insulating material wound in multiple upon said body and forming a protector therefor, another flexible casing composed of strips of insulating material wound in multiple directly upon the first-named casing, relatively small fibrous strands interbraided with the strips of one of said casings, and an outer fabric protective covering enclosing the insulated and encased conductor. 100

In testimony that we claim the foregoing as our invention we have signed our names 115 this 28th day of June, 1926.

CERTIFICATE OF CORRECTION.

Patent No. 1,863,354.

June 14, 1932.

EDWIN J. SCHNEIDER ET AL.

It is hereby certified that error appears in the printed specification of the above numbered patent requiring correction as follows: Page 1, line 76, after "heavy" insert the words body of a flexible plastic insulating compound 6 such as rubber. At 7, we have shown a casing or; and that the said Letters Patent should be read with this correction therein that the same may conform to the record of the case in the Patent Office.

Signed and sealed this 6th day of September, A. D. 1932.
